(57) **CLAIM**

The ornamental design for a heater lamp, as shown and described.

DESCRIPTION

FIG. 1 is a front view of a heater lamp showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view 1 thereof; and,

FIG. 8 is a perspective view 2 thereof.

The claimed design is indicated by the relatively dark portions in the figures. The broken lines illustrate a boundary of the claimed design. The broken lines and the de-emphasized and relatively light portions form no part of the claimed design.
